UNITED STATES PATENT OFFICE

HARRY D. LOCKWOOD, OF KANSAS CITY, KANSAS

SIGN

Application filed June 15, 1931. Serial No. 544,390.

This invention relates to display structures and particularly luminous signs, the primary object of the invention being the provision of specific structure as regards the disposition of display panel, frame therefor, and an interposed gas-filled tube which may be seen when the sign is viewed from either side thereof.

One of the objects of the instant invention is the contemplation of a luminous sign 10 wherein is incorporated an outlining, transparent tube, secured in a protected position around the edge of the display panel of the sign in a manner permitting its being seen from either side of the sign.

15 Heretofore signs utilizing gas-filled tubes of glass have been constructed with each side of the sign presenting a separate set of tubes and in no instance did a single tube attract attention from both sides of the opaque display panel. In signs of size, use of a large amount of tubing is expensive, which factor precludes the ordinary user from displaying a sign where both sides thereof require what is usually called, neon lighting.

20 One of the objects of this invention is, therefore, the provision of a sign structure wherein is embodied a lighting tube which lies around the edge of the display panel, in the same plane therewith, and where it may 25 be viewed from either side of the sign.

A yet further object of the instant invention is to provide a sign as above specified, wherein is also incorporated a canopy which forms a housing for the flood lamps, as well 35 as a separate housing for the electrodes associated with the panel-encircling lighting tube.

30 A more specific object of this invention is the contemplation of novel spacer clamps, which combine with frame, panel and tube to rigidly secure the same in proper relation.

Further minor objects of this invention will appear during the course of the following specification, referring to the accompanying drawing, wherein the preferred and one modified form of the invention has been 45 illustrated, and wherein:

Figure 1 is a side elevation of a display sign made in accordance with this invention and having parts broken away for clearness.

Fig. 2 is a vertical cross section through the sign, taken on line II--II of Fig. 1.

Fig. 3 is an enlarged, fragmentary, detail view through the spacer clamp taken on line III--III of Fig. 1, and,

Fig. 4 is a similar sectional view, but showing a modified form of construction which embodies a plurality of lighting tubes in place of a single one.

In setting down the specific construction and combination of parts as they are illustrated in the drawing, like reference characters will be used to designate similar parts of the sign structure. As is customary, a sign wherein this invention might best be utilized includes an opaque display panel 6 which usually has some matter painted or printed on each side thereof. It is to this matter on panel 6 that it is desired to draw the attention of the observer and to do this in economical fashion, panel 6 is supported within frame 8 with a lighting tube 10 extending entirely around panel 6 between the edges thereof and said frame 8. Tube 10 lies in the same plane as panel 6 and is maintained in position by unique spacer clamps clearly illustrated in Fig. 3. These spacer clamps consist of a major member 12 and a secondary member 14. Major member 12 extends from frame 8 to panel 6, bridging the space therebetween, and rigidly secured in place by bolts 16. Frame 8 is T-shaped in cross section and the web 18 of frame 8 projects between members 12 and 14 of the spacer clamp, as illustrated in Fig. 3.

In the preferred form of the invention, secondary clamp 14 terminates an abutting relation with the edge of panel 6. Both members 12 and 14 are arcuate in cross section between panel 6 and frame 8 to encircle and support tube 10. Obviously, the only part of tube 10 not visible from either side of the sign is that small portion covered by members 12 and 14 of the spacer clamps. As the luminous tube 10 is attracting attention to the sign, the matter upon panel 6 is flooded with light from lamps 20, supported within canopy 22, formed along what is preferably the upper edge of panel 6. Brackets

100

24 may be supplied to hang the sign in the usual manner.

Within canopy 22 is housed transformer 26, which may be used to convert electrical energy utilized in the tube 10. Housing 28 forms a partition longitudinally within canopy 22 and encases electrodes 30 which are formed at the end of tube 10.

In the modified form shown in Fig. 4, each 10 spacer clamp is formed of members 100 and 102 which are substantially like member 12, but which have a plurality of arches formed therein, between which a like number of tubes 104 may be interposed. Bolts 106 may 15 be used to secure members 100 and 102 in place in a manner which will properly assemble panel 6, frame 8 and the desired number of tubes 104.

Having thus described the invention, what 20 is claimed as new and desired to be secured by Letters Patent is:

1. A luminous sign comprising an opaque display panel; a frame extending entirely around the edge of said panel in spaced relation thereto and in the same major plane therewith; a luminous tube extending around said panel between the periphery thereof and said frame; and a plurality of spacer clamps engaging said panel and frame having 25 a formed body intermediate the points of connection, whereby said tube is maintained in the plane of said panel and is visible from either side of said sign.

2. A luminous sign comprising a display panel; a canopy along one edge of said panel; a frame around the edge of said panel in spaced relation thereto; a tube around said panel inside of said frame and spacer clamps 30 engaging said panel and frame having a formed body intermediate said points of connection whereby to engage and maintain said tube in the plane of said panel.

3. A luminous sign comprising a display panel; a frame around the edge of said panel in spaced relation thereto; a tube around said panel inside of said frame and spacer clamps 45 engaging said panel and frame having a formed body intermediate said points of connection whereby to engage and maintain said tube in the plane of said panel.

In testimony whereof, I hereunto affix my signature.

HARRY D. LOCKWOOD.
